WASHING MACHINE

John E. Vеторино, Fairhaven, Mass., Frank Vеторино, Cincinnati, Ohio, and Joseph E. Vеторино, New Bedford, Mass., assignors, by mesne assignments, to Continental Laundry Machinery Co. Inc., New Bedford, Mass., a corporation of Massachusetts

Application December 22, 1939, Serial No. 310,656

5 Claims. (Cl. 68—20)

Our invention relates broadly to washing machines and more particularly to combined washing and drying machines of the rotary tumbler and extractor type as exemplified in U. S. Letters 5 Patent No. 1,979,237 to Frank Vеторино, dated October 30, 1934, and over which the instant invention is designed as an improvement.

The principal object of the present invention is to provide in a machine of the type identified 10 an improved drive for a plurality of combination tumbler and extractor cylinders, whereby said cylinders may be revolved in unison about a common axis in the extracting operation, or, rotated about a common axis at a right angle to the axis 15 of revolution to function as tumblers and spinners in the washing and drying operations.

Another object is to provide practical and efficient means for introducing fluid or air under 20 pressure into the cylinders after the extracting operation and to complete drying.

Another object is to provide in the drive for ease of control in switching the drive from revolving to rotary, and vice versa, so as to obviate shock and jar and thereby prolong the 25 life of the mechanism.

Still another object is to provide a drive for the purpose above set forth which is simple in construction, adapted for comparatively high speed operation and to withstand prolonged use, and is economical to service, install and manufacture.

Other, and subordinate, objects are also comprehended by our invention, all of which, together with the precise nature of our improvements, will be readily understood when the succeeding description and claims are read with reference to the drawings accompanying and forming part of this specification.

In said drawings:

Figure 1 is a view in side elevation of a preferred embodiment of our invention with parts broken away and shown in section,

Figure 2 is a view in transverse section taken 45 on the line 2—2 of Figure 1 looking in the direction indicated by the arrows,

Figure 3 is a view in horizontal section taken on the line 3—3 of Figure 1 looking in the direction indicated by the arrows.

Figure 4 is a similar view taken on the line 4—4 of Figure 2 looking in the direction of the arrows,

Figure 5 is a diagrammatic view in side elevation illustrating the position indicating means 55 for the cylinders, and

Figure 6 is another diagrammatic view further illustrating said position indicating means.

Referring now to the drawings by numerals, the illustrated form of our invention comprises, as the basic element thereof, an upright cylindrical casing 1 having a pair of angle iron reinforcing bands, 2, 3 around its upper and lower ends, respectively, suitably secured thereto. Above the lower end thereof, at any suitable distance, the casing 1 has suitably secured therein 5 a circular bottom 4 reinforced by radial flanges 5 beneath the same and having an axial aperture 6 therein for a purpose presently seen. Mounting the upper end of the casing 1 is a dome-shaped top or cover 7 of circular form provided 10 with an angle iron reinforcing band 8 around the lower edge thereof, bolted, as at 8', to the flange 2. Extending from one side of the cover 7, laterally, is a bracket 9. A pair of inlet pipes 10 for air under pressure extend from diametrically opposite sides of the casing 1 in horizontal alignment and substantially midway between the bottom 4 and the top of the casing. A suitable drain plug is provided in the bottom 4 as indicated at 10'. An axial aperture 11' is provided 15 in the cover 7 for a purpose presently seen. Intermediate the pipes 10 and at the same level as said pipe, a circular door 11 is hinged to the casing 1, as at 12, for outward opening, said door closing on an annular flange 13 surrounding a 20 circular door opening 14 provided in said casing. A pair of keeper bolts 15 are hinged to the flange 13 as at 15', to be swung into bifurcated edge lugs 16 on said door 11, said bolts and lugs being constructed for coacting camming action to 25 force the door 11 tight against said flange.

Within the casing 1 is a pair of combined tumbler and extracting cylinders 17 of duplicate construction having concavo-convex front and back sides 18, 19, respectively, and detachably secured together coaxially in back-to-back spaced apart relation by means of a short horizontal shaft 20 tapered at its ends, as at 21, to fit into axial sockets, as at 22, provided on the backs of the cylinders 17, said cylinders being clamped to 40 the ends of the shaft 20 in any suitable manner as by a bolt 23 passing through the back of each cylinder and into said shaft. The cylinders 17 are perforated, as at 24, with the exception of the backs 19, and said backs arch inwardly and 45 the fronts outwardly. Each cylinder 17 is provided with an annular door frame 25 suitably secured to the front thereof concentrically of the cylinder and having a grooved inner edge 26. A circular door 27, preferably arched inwardly of 50

55

the cylinder, and perforated, is provided for each cylinder, said door fitting within the frame 25 of the cylinder and being detachably secured therein by means of an edge lug 28 fitting into 5 the groove 26 of the frame 25, and a pair of latch bolts 29 suitably mounted on the outer face of the door to be projected into said groove under the urge of springs as at 30. As best shown in Figure 3, the doors 27 are slightly smaller than 10 the door frame openings 14 so as to be removed through the latter.

Coming now to the drive, and related parts, surmounting the cover 7 is a circular cap-like clutch housing 31 having a bottom edge flange 15 32 by means of which and bolts 33 said housing is secured to said cover concentrically thereof.

Within the top of the housing 31 is a driven pulley 34 horizontally disposed and having a depending circumferential skirt providing a clutch flange 35. Within the pulley 34 is a bevel gear 36 having the hub thereof keyed, as at 37, in the hub of the pulley 34 for rotation thereby. The pulley 34 and gear 36 are rotated axially of 20 the casing 1 on a bolt-like arbor 38 extended 25 through the top of the housing 31 and having a nut 39 on the upper end thereof. A cap 40 suitably fixed to the housing 31 covers the nut 39.

The pulley 34 and gear 36 are adapted to be 30 driven by an electric motor 41 bolted, as at 42, to the beforementioned bracket 9 with the armature shaft 43 thereof upright. A belt 44, of the multiple band type, extends from a pulley 45 fast on the armature shaft 43 to the pulley 34, said pulleys being suitably grooved for the specified 35 type of belt as shown in Figure 2. The belt 44 extends through a suitable throat 46 provided in the appropriate side of the housing 31.

A flat hollow gear casing 46 is provided in the vertical axis of the casing 1 in upstanding position 40 for rotation therein and to extend at its upper end within the bottom of the housing 31, said gear casing having at said end, a radial circular flange 47. The lower end of the gear casing 46 is provided with a trunnion 48 extending through 45 a suitable stuffing box 49 fitting in the opening 6 and bolted, as at 50, to the bottom of the casing 1, said lower end being stepped and supported in a suitable end thrust bearing assembly 51 bolted, as at 52, to the bottom structure of the casing 50 1 beneath said bottom. The upper end of the gear casing 46 is provided with a tubular neck 53 extending through a ball bearing assembly 53' fitted into the aperture 11' in the cover 7 and bolted to said cover as at 54.

55 The gear casing 46 functions as a carrier for the horizontal shaft 20 which is extended through the sides thereof in the axis of the pipes 10 and rotatably mounted on said casing by means of ball bearing assemblies, as at 55, fitted into and suitably secured in annular flanges, as at 56, on said sides.

The drive is transmitted from the gear 36 to the shaft 20 to rotate the combined tumbler and extractor cylinders 17 about a horizontal axis 65 and from the said gear and the clutch flange 35 to the gear casing 46 to revolve the cylinders 17 in unison about the vertical axis of the casing 1 all as follows.

70 Fixed to the flange 47 of the gear casing 46, concentrically thereof and subjacent to the pulley 34, is a cup-like brake drum 56. A metallic brake band 57 is provided around the drum 56 with opposite ends thereof extended out of the housing 31 at one side thereof through a suitable throat 58 in said housing.

The brake band 57 is attached, intermediate its ends, to said housing 31 by means of a keeper extension 59 pivoted to said housing as at 60. A hand lever 61 is provided for operating the ends of said band 57 so as to tighten the band against 5 said drum, said lever being fast on the upper end of the shaft 62 rotatably mounted in lateral ears 63 on the housing 31, the shaft having fast thereon a cross-arm 64 suitably connected to said ends of the brake band 57, as indicated at 65. The arrangement of the hand lever 61 and the described connection between the same and the band 57 is such that movement of said lever to either side of a central normal position will effect tightening of the band. A detent 66 cooperating with teeth 15 67 on one of said ears 63 provides for holding the lever 61 in operated position.

The brake drum 56 has upstanding therefrom in the center thereof a tubular bearing 68. A transverse shaft 69 is extended through the upper 20 end of said bearing 68. A pair of segmental friction clutch shoes 70 are slidably mounted on opposite ends of said shaft 69, respectively, exteriorly of the bearing 68 and for movement into and from clutching relation to the clutch flange 25 35. A pair of light coil springs 71 are sleeved onto opposite ends of said shaft 69, respectively, between the brake shoes 70 and collars 72 on said shaft, so as to yieldingly urge said shoes into disengaged position relative to the flange 35 while 30 permitting said shoes to be engaged with said flange under the action of centrifugal force. A small sprocket wheel 73 is rotatably mounted on the shaft 69 between the sides of said bearing 68 so that said wheel is confined in said bearing 35 against lateral movement, ball-bearing assemblies 74 being provided between said shaft and wheel. The beveled gear 36 drives the sprocket wheel 73 through the medium of a beveled gear 75 fast on the hub of said wheel. The sprocket 40 wheel 73 is operatively connected to the shaft 20 by means of a large sprocket wheel 76 fast on said shaft within the gear casing 46, and a sprocket chain 77 extending between said sprocket wheels and passing out of said casing by way 45 of the neck 53. A pair of opposed idler sprockets 78 are suitably mounted in the gear casing 46 upon opposite sides of the neck 53 and adjacent the same and between which said chain 77 is extended.

The casing 1 is equipped with suitable inlet and outlet pipes for liquid and air, respectively, and designated 80, and 81.

Means are provided on the brake drum 56 and the clutch housing 31 for indicating the exact 55 position in which to stop revolution of the cylinders 17 to axially align the doors 27 with either the inlet pipes 10 or the door opening 14. For this purpose a sight glass 82 is provided in the clutch housing 31 in position to render visible 60 therethrough a plurality of arrow-like pointers depending from the bottom of the brake drum 56 adjacent the lower edge thereof. The sight glass 82 is provided with a center arrow-like gage mark 83. The pointers are located on the brake drum 65 56 in spaced apart 90 degree relation to provide two diametrically opposite pairs 84, 85, those of one pair being arranged to register with the mark 83 when the doors 27 are aligned with the pipes 10 and those of the other pair registering with 70 said mark when one or the other of said doors 27 is aligned with the door opening 14. One pair of pointers, 84, or 85, as the case may be, is distinguished from the other pair as by coloring, not shown, so as to indicate whether said doors 27 are 75

aligned with the pipes 10 or the door opening 14. Referring now to the operation in extracting, with the hand lever 61 set in the intermediate position, as shown in Figure 4, and the motor 41 energized, under the inertia of the combined tumbler and extractor cylinders 17, the beveled gear 36 carries the beveled gear 75 around with the same, thereby revolving the sprocket wheel 73, shaft 69, brake drum 56, and gear casing 46 about the vertical axis of the latter, whereby said cylinders are revolved about a common vertical axis of revolution until a predetermined speed of operation is attained. At this point, the clutch shoes 70, under the action of centrifugal force, are engaged with the clutch flange 35 of pulley 34 and drive transmitted from said flange to the gear casing 46 through said shoes 70, the shaft 69, and brake drum 56. By operating the hand lever 61 in the manner already described to tighten the brake band 57 against the brake drum 56, the latter may be retarded and stopped together with gear casing 46 and said cylinders 17. Under this condition, the clutch shoes 70 will be disengaged from the clutch flange 35 by the springs 71, such disengagement occurring as soon as the point of deceleration is reached at which the springs 71 overcome the centrifugal force acting to engage said shoes. As soon as disengagement of the clutch shoes 70 occurs, the drive is transmitted from the beveled gear 36 to gear 75 and thence by the described sprocket and chain drive to the shaft 20 so as to rotate said shaft together with the cylinders 17 about the axis of the shaft, to accomplish the tumbling and drying operation.

After extracting, revolution of the cylinders 17 about their vertical axis of movement is stopped in a manner which will be clear to register the doors 27 with the pipes 10 and by the aid of the described position indicating means, air under pressure is blown into said cylinders by way of said doors while said cylinders are being rotated about their horizontal axis of movement to complete the drying. By revolving the cylinders 17 until the doors 27 thereof are alternately opposite the door 11, the doors 27 may be detached from the cylinders in the manner already described and removed through said door 11 so that said cylinders may be loaded as desired.

The foregoing will, it is believed, suffice to impart a clear understanding of our invention without further explanation.

Manifestly the invention, as defined, is susceptible of modification without departing from the inventive concept and right is herein reserved to such modifications as fall within the scope of the subjoined claims.

What we claim is:

1. In a machine of the class described, a main casing, a pair of combination tumbler and extractor cylinders in said casing, a shaft connecting said cylinders together in relatively fixed axially spaced relation for rotation in unison about a horizontal axis, a shaft carrier upstanding in the vertical axis of said casing between said cylinders and rotatably mounted therein for driving to revolve said shaft and cylinders in unison about said vertical axis, and a motor drive for rotating said shaft and carrier, selectively, comprising a driven pulley surmounting said casing and rotatable on said vertical axis, a brake drum fast on the upper end of said carrier intermediate said pulley and casing, a friction clutch assembly carried by said drum between said pulley and drum operative under the action of centrifugal force to connect said pulley to said drum in driving relation to

tion thereto at a predetermined speed of operation of said drum, a planetary gear drive between said pulley and drum and driven by the pulley, a sprocket and chain drive for said shaft extending into said drum and operative by said planetary gear drive, and means to impose variable friction against said drum at will. 5

2. In a machine of the class described, a main casing, a pair of combination tumbler and extractor cylinders in said casing, a shaft connecting said cylinders together in fixed axially spaced relation for rotation in unison about a horizontal axis, a hollow shaft carrier upstanding in the vertical axis of said casing between said cylinders and rotatably mounted therein for driving to revolve said shaft and cylinders in unison about said vertical axis, and a motor drive for rotating said shaft and carrier, selectively, comprising a driven pulley surmounting said casing and rotatable on said vertical axis, a brake drum fast on the upper 10 end of said carrier intermediate said pulley and casing, a friction clutch assembly carried by said drum between said pulley and drum operative under the action of centrifugal force to connect said pulley to said drum in driving relation there- 15 to at a predetermined speed of operation of said drum and including a cross shaft mounted on said drum for revolution therewith, a planetary gear drive between said pulley and drum and driven by the pulley and including a gear pinion 20 freely rotatable on said cross shaft, driving connections between said pinion and the first mentioned shaft revolving about said vertical axis, and means to impose variable friction against said 25 drum at will. 35

3. In a machine of the class described, a main casing, a pair of combination tumbler and extractor cylinders in said casing, a shaft connecting said cylinders together in fixed axially spaced relation for rotation in unison about a horizontal 40 axis, a hollow shaft carrier upstanding in the vertical axis of said casing between said cylinders and rotatably mounted therein for driving to revolve said shaft and cylinders in unison about said vertical axis, and a motor drive for rotating said 45 shaft and carrier, selectively, comprising a driven pulley surmounting said casing and rotatable on said vertical axis, a brake drum fast on the upper end of said carrier intermediate said pulley and casing, a friction clutch assembly carried by said 50 drum between said pulley and drum operative under the action of centrifugal force to connect said pulley to said drum in driving relation there- 55 to at a predetermined speed of operation of said drum and including a cross shaft mounted on said drum for revolution therewith, a planetary gear drive between said pulley and drum and driven by the pulley and including a gear pinion freely rotatable on said cross shaft, a driving connection between said pinion and the first men- 60 tioned shaft revolving about said vertical axis, and means to impose variable friction against said drum at will, said driving connection comprising, a sprocket wheel fast on said first mentioned shaft, a sprocket wheel freely rotatable on said 65 cross shaft and operative by said gear pinion, and a sprocket chain connecting said sprocket wheels.

4. In a machine of the class described, a main casing, a pair of combination tumbler and extractor cylinders in said casing, a shaft connecting said cylinders together in relatively fixed axially spaced relation for rotation in unison about a horizontal axis, a shaft carrier upstand- 70 ing in the vertical axis of said casing between said 75

- cylinders and rotatably mounted therein for driving to revolve said shaft and cylinders in unison about said vertical axis, and a motor drive for rotating said shaft and carrier, selectively, comprising a driven pulley surmounting said casing and rotatable on said vertical axis, a brake drum fast on the upper end of said carrier intermediate said pulley and casing, a friction clutch assembly carried by said drum between said pulley and drum operative under the action of centrifugal force to connect said pulley to said drum in driving relation thereto at a predetermined speed of operation of said drum, a planetary gear drive between said pulley and drum and driven by the pulley, a sprocket and chain drive for said shaft extending into said drum and operative by said planetary gear drive, and means to impose variable friction against said drum at will, said last mentioned means comprising a hand lever pivotally mounted alongside said drum, and a brake band trained around said drum and having ends connected to said

lever for operation thereby to tighten the band about the drum.

5. In a machine of the class described, a main casing, a pair of combination tumbler and extractor cylinders in said casing, a shaft connecting said cylinders together in fixed axially spaced relation for rotation in unison about a horizontal axis, a shaft carrier upstanding in the vertical axis of said casing between said cylinders and rotatably mounted in said casing for driving to 10 revolve said shaft and cylinders in unison about said vertical axis, a pair of axially disposed perforated doors in the outer sides of said cylinders, respectively, and a pair of inlet pipes at opposite sides of said casing, respectively, opening 15 thereto at the level of said doors for blasting fluid under pressure into said casing and against said doors to pass through the latter into the cylinders.
